UNITED STATES PATENT OFFICE

ELWIN H. KIDDER, OF CHICAGO, ILLINOIS, ASSIGNOR TO LINK-BELT COMPANY, OF CHICAGO, ILLINOIS, A CORPORATION OF ILLINOIS

CAR DUMP

Application filed January 31, 1927. Serial No. 164,771.

This invention relates to a car dump. It includes generally a rolling frame into which the car may be moved. The frame is mounted on a track so that it is bodily rolled. It is provided with mechanism so that as it is rolled, the car is automatically clamped into position within the frame. One object of the invention is to provide with such an apparatus means for moving the car and frame laterally as they are tipped. Another object of the invention is to provide means whereby the car and frame are timed normally under the influence of gravity to return to the original upright position when free to do so. Other objects will appear throughout the specifications and claims.

The invention is illustrated more or less diagrammatically in the accompanying drawings, wherein—

Figure 1 is an end elevation.

Figure 2 is a vertical section on line 2—2 of Figure 1 on an enlarged scale.

Figure 3 is an enlarged fragmentary end elevation with parts in section.

Figure 4 is a vertical section taken on line 4—4 of Figure 3.

Like parts are indicated by like characters throughout.

A, A are beams carrying tracks A¹, A¹. These tracks are preferably double as shown. One end of the beams A is carried on a foundation A². It is further supported at its other end and adjacent its center on columns A³, A³ which are supported on foundations A⁴.

B, B are generally circular members provided each on its periphery with a track portion B¹, having preferably a raised central portion B². The members B are joined by reinforcing and strengthening parts which may be of any suitable construction. B³ is a box shape frame in which counterweights and certain clamp controlling mechanisms may be mounted. These are not shown in greater detail as their particular construction forms no part of the present invention.

C is a car supporting frame having upon it tracks C¹ C¹. Beneath the frame and attached to it are a plurality of contact or bearing portions C². C³ C³ are wheels

mounted for rotation in the members B. The portions C² are in contact with the rollers C³ and thus the frame C is supported upon the rollers and is adapted to have limited lateral movement.

D is an opening in each of the members B and within this opening the car frame C is mounted. D¹ is a car contacting and material controlling wall. It is preferably formed of wood and the car is moved over 60 against it during the tipping operation.

D² D² are clamps. Their details of construction form no particular part of the present invention and will therefore not be fully described. It is sufficient to say that when 65 a car is run upon the dumper, these clamps automatically or otherwise hold the car in position so that dumping may be properly carried out.

E indicates a car in the dumper.

F is a hoisting mechanism of any suitable type. F¹ F¹ are main dumping cables and are joined to the members B at F². Each of these cables passes over a sheave F³. F⁴ F⁴ are slip preventing cables. Each is attached 75 at one end to one of the members B as at F⁵ and at its other end to the frame-work A as at F⁶. F⁷ F⁷ are additional slip preventing cables. Each is attached at one end to one of the members B as at F⁸ and at the 80 other end each is attached to a member secured to the foundation A² as at F⁹. The cables F⁴ and F⁷ serve to prevent slipping or skidding of the rolling assembly in either direction so that when the member is rotated 85 toward the dumping position along the track, it will rotate positively.

G is a hopper having an open upper receiving portion and a restricted downwardly discharging portion G¹. G² is a closure for 90 the discharging portion movably mounted upon supports G³.

At one or more points on the frame C and preferably adjacent each end, there is mounted a roller H.

J is a controlling lever mounted for rotation at J¹ in a bearing J² which is supported upon the foundation A². When the dumper is in the upright or undumped position as shown in full lines in Figures 1, 3, and 4 par.

ticularly, this lever J is in contact with the roller H and prevents lateral movement of the frame C. J⁴ and J⁵ are stops for the lever J.

5 K is a bearing supported upon the foundation A². K¹ is a shaft journaled in the bearing and having fixed upon it a lever K². K³ is a connecting link joined at one end to the outer end of the lever K² and at the other end to the extension J³ of the lever J. K⁴ is a second lever fixed on the shaft K¹ and carrying adjacent its outer end an adjustably mounted counterweight K⁵. K⁶ is a portion of the lever K⁴. It carries in its outer end 10 a roller K⁷ which normally bears against the track portion B¹.

L is a shaft or rod extending through the carrier frame and also extending through a portion of the car supporting frame. L¹ is 15 a spring positioned by the member L and L² is a collar positioned also on the member L contacting at one end with the frame C and at the other with the spring L¹.

While I have shown an operative device, 20 still it will be obvious that many changes might be made in the size, shape and arrangement of parts without departing materially from the spirit of my invention and I wish, therefore, that my showing be taken as in a 25 sense diagrammatic.

The use and operation of the invention are as follows:

The dumper is shown in the loading position in Figure 1 in full lines. In that position a car is moved upon it. The hoisting mechanism is then put in operation and the hoisting cables are drawn in causing the dumper frame to roll laterally along the tracks. As this movement commences, the 35 40 clamps, preferably automatically operated, come into position to engage and hold the car in proper position.

As the dumper rolls to the left as shown particularly in Figure 1 and in detail in Figure 3, the roller K⁷ is in engagement with the track on the member B. As the dumping frame assembly rolls it tends to move away from the roller K⁷. As this movement continues the lever K⁴ and the counterweight K⁵ 45 tends to rotate downwardly and thus through the levers K² and the connecting links K³ and the levers J, the framework C is permitted to move laterally at first under the influence of the spring L¹ which is normally under compression when the parts are in the position 50 shown in Figure 1. Thus as the result of the rolling of the car carrying assembly the car frame C is freed for lateral movement, the movement occurring initially as a result of 55 the expansion of the spring. This action takes place because the downward movement of the lever K⁴ through the linkage above mentioned causes the lever J to move to the left as shown in Figures 1 and 3 and thus to 60 permit the frame C to be moved to the left 65

by the spring. Thus as the dumping assembly is rolled laterally the car frame is moved automatically laterally first by the spring and then by the influence of gravity as the dumping movement is continued until the car lies 70 against the part D¹.

As the dumping is continued, the car and the frame assembly which holds it are rolled laterally and when the car is over the receiving hopper, the tipping movement has progressed sufficiently to cause some of the contents of the car to be discharged. The tipping movement may be continued until the car is practically upside down. When the dump is complete the dumping assembly is 75 rotated in the reverse direction and moves backward again to the original position. As it reaches the original position, the lever assembly above described operates again and again the levers J engage the rollers H and 80 regulate the movement and position of the frame C.

During the rolling tipping movement, the cables F⁴ wind about the members B and prevent their slipping. This is particularly important where the tracks are at an incline as shown in the present construction and where there is a tendency for the rotating frame assembly to slip or skid down hill while the hoisting mechanism is rolling it uphill. 85

When the car carrying assembly has rolled away from the filling position, so that the lever J is out of contact with the roller H, the movement of the lever J to the left, as shown in Figure 3 is limited by the stops J⁴ and J⁵. The counterweight K⁵ tends to move the lever J always to the left but as soon as the adjustable stop J⁴ has contacted the fixed stop J⁵, further movement in that direction is prevented. 95

The members F⁸ on each of the members B, in addition to their other functions, serve as stops to limit the car carrying assembly in the dumping direction. This is shown in the dotted line position in Figure 1 in which the member F⁸ is in contact with the member F¹⁰. Similar stop members F¹² are also mounted on the members B and they contact the stop members F¹¹ which are mounted on the foundation member A² when the car carrying assembly is in the upright or loading position as shown in full lines in Figure 1. 100

I claim:

1. In combination in a car handling apparatus a movable frame and a car supporting platform forming a part of such frame and adapted to have movement relative to the rest of said frame, means for moving and for controlling the movement of such platform, a movable member mounted outside of such frame and adapted when the frame is in one position to bear upon a portion of such platform to hold it against movement and adapted as the frame is moved to be itself moved by movement of the frame, to permit move- 110 115 120 125 130

ment of such platform in response to such movement of the frame, a linkage positioned outside of the frame, adapted to be moved in response to it and to move the above mentioned movable member.

2. In combination in a car handling apparatus a movable frame and a car supporting platform forming a part of such frame and adapted to have movement relative to the rest of said frame, means for moving and for controlling the movement of such platform, a member pivoted outside of such frame and adapted when the frame is in one position to bear upon a portion of such platform to hold it against movement and adapted as the frame is moved, to permit movement of such platform in response to such movement of the frame.

3. In combination a car dumping assembly including a car carrying frame, a car supporting platform movably mounted within such frame, means for moving such frame laterally, means for moving and for controlling the movement of such platform within such frame, in response to such lateral movement, said means including a movable member mounted and supported outside of such frame and adapted to contact a portion of said platform, such member adapted, in response to lateral movement of the car carrying frame, to control the movement of such platform.

4. In combination, a car dumping assembly including a car carrying frame, a car supporting platform movably mounted within said frame, means for moving the frame laterally, means for moving and controlling the movement of the platform within the frame in response to the lateral movement of the car carrying frame, said means including a member mounted and supported outside of the frame and movable into contact with the platform to move the same in one direction and also movable into and out of the path of movement of the platform to control the movement of the platform in the opposite direction, said movable member being actuated in response to the lateral movement of the car carrying frame.

5. In combination in a car dumper having a car carrying frame adapted to be moved bodily and a car carrying member within such frame adapted to have motion therein, means for holding and for permitting movement of such member including a movable stop and control assembly mounted outside of such frame and contacting a part of such member, and operating mechanism adapted to contact a portion of such frame, to move in response to motion of such frame and thereby to move such stop assembly.

6. In combination in a car dumper having a car carrying frame adapted to be moved bodily and a car carrying member within such frame adapted to have motion therein,

means for holding and for permitting movement of such member including a stop and control assembly mounted outside of such frame and contacting a part of such member and operating mechanism adapted to contact a portion of such frame, to move in response to motion of such frame and thereby to move such stop assembly, such stop and control assembly including an operating member mounted for rotation, having a contacting part normally in contact with the periphery of such frame and adapted to be freed for motion in response to movement of such frame.

7. In combination in a car dumper having a car carrying frame adapted to be moved bodily and a car carrying member within such frame adapted to have motion therein, means for holding and for permitting movement of such member including a stop and control assembly mounted outside of such frame and contacting a part of such member and operating mechanism adapted to contact a portion of such frame, to move in response to motion of such frame and thereby to move such stop assembly, such stop and control assembly including a pivoted lever adapted to contact a portion of said carrying member and a second operating lever provided with a contact part adapted normally to contact a portion of said frame and adapted to be freed for movement by the bodily motion of such frame and having a linkage connecting the pivoted lever and the operating part whereby movement of the operating part is transmitted to the said first lever.

8. In a car handling apparatus, a car supporting assembly including a frame mounted for bodily lateral movement and means for moving such frame, an element of such assembly movably mounted in such frame, means for holding such element against movement and means for moving it and controlling its movement in response to the lateral movement of said frame, such means including a part mounted outside of and engaging a part of such element, a second part in contact with a portion of such frame, the last mentioned part being adapted to move in response to lateral movement of such frame and thereby to operate said first part to permit movement of such element, and means for limiting the movement of said first mentioned part.

9. In a car handling apparatus, a car supporting frame mounted for bodily lateral movement and means for moving such frame, an element of such assembly movably mounted in such frame, means for holding such element against movement and means for moving it and controlling its movement in response to the lateral movement of said frame, such means including a lever supported outside of such frame and engaging a part of such element, a second lever in contact with a portion of such frame, the last mentioned

lever being adapted to move in response to lateral movement of such frame and thereby to operate said first mentioned lever to permit movement of such element and means for limiting the movement of said levers.

10. In a car handling apparatus, a car supporting frame mounted for bodily lateral movement and means for moving such frame, an element of such assembly movably mounted in such frame, means for holding such element against movement and means for moving it and controlling its movement in response to the lateral movement of said frame, such means including a lever pivoted on a fixed support outside of such frame and engaging a part of such element, a second lever pivoted on a different fixed support and in contact with a portion of such frame and a linkage connecting the two levers, the last mentioned lever being adapted to move in response to lateral movement of such frame and thereby through said linkage to operate said first mentioned lever to permit movement of such element and means for limiting the movement of said levers.

Signed at Chicago, county of Cook, and State of Illinois, this 21st day of January, 1927.

ELWIN H. KIDDER.
